UNITED STATES PATENT OFFICE

2,246,189

BAR HANGER

Edward H. Rugg and George Carlson, Bridgeport,
Conn., assignor to General Electric Company, a
corporation of New York

Application December 8, 1938, Serial No. 244,630

4 Claims. (Cl. 248—57)

This invention relates to an adjustable support for wiring material, and more particularly to an adjustable bar hanger and stud for supporting electrical fittings such as outlet boxes or the like.

It is an object of the invention to provide an improved construction and arrangement in devices of the type described in which the bar hanger may be adjusted for positioning between supports having various spacings and in which the bar hanger and stud may be adjusted to support various sizes of outlet boxes.

In the accompanying drawing Fig. 1 is an elevational view showing the bar hanger and stud mounted between spaced supports; Fig. 2 is a plan view of the device shown by Fig. 1; Fig. 3 is a plan view similar to the showing of Fig. 2, but with the device mounted between supports spaced apart a shorter distance; Fig. 4 is a view, partly in section, of the stud showing a positioning tag mounted thereon; Fig. 5 is a side view of the stud and positioning tag, and Fig. 6 illustrates the positioning tag which is mounted on the stud.

Referring to the drawing, the invention employs a bar hanger 10 which may be of rectangular shape and which is preferably constructed of strong and rigid material capable of withstanding considerable weight. The bar hanger is provided with a substantially straight intermediate portion 11 and the ends of the hanger are curved at 12 in opposite directions away from the plane of the intermediate portion to give the bar hanger a substantially S-shape. Each end of the hanger is provided with a plurality of spaced holes 13 which extend inwardly for some distance from the ends of the hanger and which are adapted to receive suitable securing means, such as nails or screws, for mounting the bar hanger on supporting members 14. In the form of the invention illustrated the supporting members 14 are the joists used in supporting the floors of buildings. The supporting joists are spaced apart a predetermined distance, depending upon the particular construction employed, and the bar hanger 10 is adapted to be placed between the joists and secured thereto in order to support an electrical fitting such as an outlet box. It frequently happens, however, that the spacing between the joists will vary considerably due either to the fact that the joists are placed at odd spacings or due to inequalities in the thickness of the joists. In such situations it is necessary that the bar hanger be adjustable so that it is adaptable for the various spacings employed. By the construction described it is possible to adapt the bar hanger for various spacings of the supporting

members or joists simply by rotating the bar hanger about its center and moving the curved ends along the supporting members until they are tangent thereto. At this point an appropriate securing means such as a nail or screw may be inserted through one of the openings 13 and driven into the supporting member to secure the bar hanger in place. This arrangement is shown most clearly by comparing the showings of Figs. 2 and 3. It will be seen from an examination of Fig. 3 that the supporting members 14' are closer together than in the showing of Fig. 2 and that the bar hanger has been rotated to move the extreme ends of the hanger away from the side of the supporting members and the bar hanger has been secured to the members at the points which are tangent thereto by means of a nail or screw inserted through the appropriate opening 13.

Cooperating with the bar hanger 10 is a stud 15 having a body provided with a slot 16 at one end for receiving the bar hanger 10 and provided with a threaded extension 17 at the other end for mounting an outlet box 18. The threaded extension 17 is recessed, as shown at 19, for the reception of a screw 20 which extends through the body of the stud into the slot 16 where it engages the bar hanger 10. In order to lock the stud in correct position upon the bar hanger, it is only necessary to tighten down on the screw 20 by means of a screw driver which may be inserted through the open end of the outlet box. A nut 21 is threaded on to the extension 17 in order to secure the outlet box thereon. In mounting an outlet box on the stud, the nut 21 is removed and the threaded end 17 inserted through an appropriate opening in the bottom of the outlet box and thereafter the nut 21 is replaced and tightened down on the bottom of the box to retain it in position.

It will be seen that the stud is adapted to support outlet boxes of various sizes such as $\frac{1}{2}$ " boxes, 1" boxes, etc. It is necessary in installing outlet boxes to position the top of the box correctly in accordance with the level of the finished plaster coat or other finished surface. This means that the bar hanger 10 must be placed at various levels above the bottom of the joists 14 depending upon the size of the outlet box which is to be supported by the bar hanger. In order to accomplish this result, a positioning means comprising a tag 22 is employed which is mounted directly upon the stud. To mount the positioning tag in the manner indicated a hole 23 is formed at one end which receives the threaded extension 17 and thereafter the nut 21 is threaded on the

extension to hold the tag in position. The tag is formed of paper and is provided with indicia 24 marked in accordance with the size of outlet box which is to be mounted on the stud. The indicia include lines 28 which extend across the face of the tag and which are arranged vertically so that they extend below the stud body, the tag being bent at the point 26 which coincides with the $\frac{3}{4}$ inch and $\frac{1}{2}$ inch indicia. The stud and hanger are assembled and sold as a unit with the tag 22 mounted on the stud as shown in Figs. 4 and 5, and with the stud slidably mounted on the hanger as shown in Figs. 1 to 3.

According to the invention, the hanger 10 is positioned correctly simply by sliding the stud 15 along the hanger until the appropriate indicating line 28 is in alignment with the lower edge 14" of the supporting member or joist 14. The indicating line is chosen to conform to the size of outlet box to be mounted on the hanger. For example, suppose a 1 1/2 inch outlet box is to be supported by the bar hanger. The stud 15 is slid along the hanger over the curved portion 12 until it is immediately adjacent the supporting member or joist 14, and the bar hanger is then moved up or down until the edge of the joist is in alignment with the 1 1/2 inch indicating line 28, this position being shown in Fig. 1. The bar hanger is then nailed in the adjusted position. The stud is then slid along the bar hanger to the other end of the hanger and this end is likewise positioned correctly in accordance with the aforementioned procedure. In this manner the bar hanger is quickly and accurately positioned in height between the supporting members or joists 35 to accommodate the size of outlet box to be mounted on the hanger. After the bar hanger is positioned correctly the stud is moved to a central point on the bar hanger, or to any other desired point, and the screw 26 is tightened to 40 lock the stud in the chosen position. Thereafter, the nut 27 is removed and an outlet box inserted on the threaded extension and the nut 27 replaced to hold the outlet box in position. The positioning tag 22 being made of paper may be left in 45 position or may be torn off.

By the construction described it is possible to

easily and quickly locate a bar hanger at the correct height between supporting members having various spacings so that it may support an outlet box of any chosen size. The reversely curved ends of the bar hanger make it universally adaptable for mounting on supports having a wide range of spacings. Not only do the curved ends of the bar hanger make it possible to adjust it for various spacings of the supports, but the curved portions permit the stud 15 to be slid along to a point immediately adjacent the supporting members or joists 14, so that the indicia may be easily lined up with the lower edges of the members to position accurately the ends of the bar hanger.

What we claim as new and desire to secure by Letters Patent of the United States is:

1. A bar hanger comprising a flat bar having a straight intermediate portion, one end of said bar being bent in a curve away from said intermediate portion, the other end of said bar being bent in a curve away from said intermediate portion in a direction opposite that of said first-mentioned end whereby said bar is adapted to be adjusted between supporting members spaced apart varying distances and means for securing said bar hanger to the supporting members.

2. A bar hanger comprising a rectangular metal bar of substantially S-shape whereby said bar may be adjusted between supporting members of various spacings.

3. A bar hanger comprising a metal bar of substantially S-shape whereby said bar may be adjusted between supporting members of various spacings, the opposite ends of said bar being provided with means to secure the bar to said supporting members.

4. A bar hanger comprising a metal bar of substantially S-shape whereby said bar may be adjusted between supporting members of various spacings, the opposite ends of said bar being provided with a plurality of holes extending along the length of said bar to secure said bar to said supporting members.
